UNITED STATES PATENT OFFICE.

ZACHARY TAYLOR RICKARDS, OF PHILADELPHIA, PENNSYLVANIA, AS-
SIGNOR TO THE FULTON & WALKER COMPANY, OF SAME PLACE.

DESIGN FOR A DELIVERY-WAGON BODY.

SPECIFICATION forming part of Design No. 26,808, dated March 23, 1897.

Application filed January 14, 1897. Serial No. 619,263. Term of patent 7 years.

To all whom it may concern:

Be it known that I, ZACHARY TAYLOR RICKARDS, a citizen of the United States, residing in the city and county of Philadelphia, in the State of Pennsylvania, have invented and produced a new and original Design for a Delivery-Wagon Body, of which the following is a specification.

The object of my invention is to produce a design for a wagon body, intended for the transportation of merchandise, in which shall be combined with graceful outlines a novel and ornamental form of window opening, and a new and pleasing arrangement of exterior molding or beading, as a result of which the said body presents a striking and handsome appearance.

Referring to the accompanying illustration which represents my design for a wagon body in Figure 1 in side elevation and in Figure 2 in rear elevation,—it will be observed that the side and end walls of the wagon body A, as also the roof, are slightly convex, the convexity of the side and rear walls being of such character as to cause said walls to bulge out somewhat abruptly just above the floor of the wagon body, while the remaining portions are approximately flat, and the upper edge of each of the said walls follows a convex line constituting the arc of a circle of large radius.

The wagon body is also provided with concave lines of light molding or beading, B, extending respectively along its back and both sides, somewhat below its vertical center, in arcs of circles correspondent with the arcs of

the upper convex edge lines, but reversely disposed,—with the result that the wall spaces between the upper edge of the wall,—over which the edges of the roof project slightly,—and said lines of molding B,—constitute each a panel or field having the outline of a truncated ellipse.

C are a series of vertical strips or lines of beading or light molding extending from the lines of beading B to the base of the body and curving slightly forward at their lower ends.

E are strips of light beading or molding, two being mounted or disposed on each wall of the vehicle body, and situated respectively in adjacency to, and extending from top to bottom of, the respective ends of said walls, to which the ends of the molding B connect.

D are window openings in the upper portion of the front ends of the side walls, approximately in the form of a shield but having an irregular, or, as it may be termed, serpentine, outline.

F is a door cut in the rear wall of the body.

Having thus described my invention, I claim and desire to secure by Letters Patent—

The design for a delivery-wagon body substantially as herein shown and described.

In testimony that I claim the foregoing as my invention I have hereunto signed my name this 12th day of January, A. D. 1897.

Z. TAYLOR RICKARDS.

In the presence of—

J. BONSALL TAYLOR,
F. NORMAN DIXON.
